UNITED STATES PATENT OFFICE

155,496

DESIGN FOR A TOMBSTONE

John A. Gardner, Salisbury, N. C.

Application August 2, 1948, Serial No. 147,897

Term of patent 14 years

(Cl. D79—2)

To all whom it may concern:

Be it known that I, John A. Gardner, a citizen of the United States of America, residing at Salisbury, in the county of Rowan and State of North Carolina, have invented a new, original, and ornamental Design for a Tombstone, of which the following is a specification, reference being had to the accompanying drawing, forming a part thereof.

Figure 1 is a front elevation of a tombstone, showing my new design, the reverse side being identical to the side shown;

Figure 2 is an end view of the tombstone;

Figure 3 is a top plan view of the tombstone.

I claim:

The ornamental design for a tombstone, substantially as shown, and described.

JOHN A. GARDNER.
